TRAY FOR MEDICAMENTS OR THE LIKE

Robert B. Jenkins, Box 1160, Gastonia, N.C.

Filed May 29, 1959, Ser. No. 56,138

Term of patent 14 years

(Cl. D83—1)

The dotted line showing of the syringe, cup and card in FIGURE 2 is for illustrative environmental purposes only.

The dominant features of the design reside in those portions shown in full solid lines.

I claim:

The ornamental design for a tray for medicaments or the like, substantially as shown and described.
